UNITED STATES PATENT OFFICE.

JOHN A. GROSHON, OF NEW YORK, N. Y.

COMPOUND STEAM-ENGINE.

SPECIFICATION forming part of Letters Patent No. 319,900, dated June 9, 1885.

Application filed November 10, 1884. (No model.)

To all whom it may concern:

Be it known that I, JOHN A. GROSHON, a citizen of the United States, and a resident of New York, in the county of New York and State of New York, have invented certain new and useful Improvements in Compound Steam-Engines, of which the following is a specification.

The invention relates to an improvement in compound steam-engines, and particularly to the construction and arrangement of the initial or high-pressure cylinder and the expansive cylinder, whereby when the pistons have made about one-third of their stroke the steam is cut off from the high-pressure cylinder and the steam therein turned into the expansive cylinder, whose piston has a larger area than that of the high-pressure cylinder, the effect being that the steam will continue its pressure against the piston in the high-pressure cylinder and expand within and exert at the same time pressure against the piston in the expansive cylinder, thus preserving a regularity of movement, the increased area in the expansive cylinder counteracting the effect of the decrease in the pressure in the initial cylinder.

The present invention is to be distinguished from other engines having expansive cylinders in that heretofore the piston in the high-pressure cylinder has been allowed to make a full stroke under boiler-pressure before the steam was turned into the expansive cylinder. By means of my invention the consumption of fuel is reduced to a minimum amount, and the pressure on the pistons does not vary materially throughout their stroke. The invention also admits of the use of a cut-off on a direct-acting machine without the employment of a fly-wheel, and in crank-engines to cause a uniform and unvarying pressure throughout the stroke.

In the drawings I have illustrated the invention as embodied in a direct-acting compound engine adapted for operating a duplex pump in which the steam-valves of one pump are operated by the engine of the other; but it is not to be understood, of course, that I limit the invention to this use. Its employment in combination with the pump, however, is very advantageous.

Referring to the drawings, Figure 1 is a side elevation of an engine embodying the invention. Fig. 2 is a central vertical longitudinal section through the high-pressure and expansive cylinders. Fig. 3 is a detached sectional view of one corner of the high-pressure cylinder, illustrating the first position of the inlet-valve; and Fig. 4 is a front end view of the engine, and Fig. 5 is a top view of the high-pressure cylinder of same.

Referring to the drawings, A denotes the initial or high-pressure cylinder; B, the expansive cylinder; C, the piston-rod passing centrally through said cylinders, and having secured upon it in the cylinder A the piston D, and in the cylinder B the piston E.

The steam-pipe is designated by F. It contains a valve, G, and connects with the pipe H, extending from the upper front portion to the lower rear portion of the high-pressure cylinder, as shown. The lower end of the pipe H leads to a valve-chamber, I, containing the valve J, and the upper end of said pipe leads to a similar valve-chamber, K, containing a valve, L, both chambers being cast with the cylinders.

From the valve-chamber I a port, M, leads to the back end of the cylinder A, and from said chamber also extends the passage N into the back end of the cylinder B. By means of the valve L the chamber K may be opened into the front end of the cylinder A or into the passage O, leading along the upper side of the cylinder B, in the front end thereof.

The two lower ends of the cylinder B contain steam-chambers (lettered P Q, respectively) having valves R S, and being connected by a passage, T, leading to the exhaust V. At all times during the operation of the engine when the chamber Q opens into the passage T the chamber P will be shut off therefrom. The chamber P is connected with the back end of the cylinder B by means of a port, W, and the chamber Q is connected with the front end of said cylinder by means of the port X, as indicated in Fig. 2. The exhaust V from the expansive cylinder B leads into the receiver Y, and thence into the chamber Z, whence it passes into the low-pressure cylinder a.

The rods *b* afford a means whereby the engine may be conveniently bolted to a duplex pump, if desired.

The valves *J L* will be operated by the well-known Corliss gear, (designated by *dd*), and the valves *R S* will be operated by the plate *e*, rods *f*, and arms *g*, constituting the well-known wrist motion. The Corliss gear *d* and the devices used in connection therewith to actuate the valves *R S*, as well as the low-pressure cylinder, the receiver *Y*, steam-chamber *Z*, and connecting devices are all of well-known construction in steam-engines, and are not sought to be claimed in the present application. They are illustrated, however, in connection with the cylinders *A B* for the purpose of conveying an accurate idea of the invention when embodied in a compound direct-acting engine. The elements specified as old being thoroughly understood, it will be unnecessary to describe them, except to point out their general functions when employed in connection with the invention which is the subject of this application, and which is illustrated in Fig. 2.

When in the operation of the engine the pistons *D E* are to commence their stroke, the valve *J* will be in the position illustrated in Fig. 3, and steam will pass from the chamber *I* through the port *M* into the back end of the cylinder *A*, and will move the piston toward the front end of the cylinder. After the piston has made about one-third of its stroke the valve *J* will be moved to the position shown in Fig. 2, thereby cutting off the steam in the chamber *I* and opening the passage *N*, the effect being that a portion of the steam already in the cylinder *A* will pass into the back end of the cylinder *B*, where it will expand against the piston *E*, and, in connection with the pressure in the back end of the cylinder *A*, will move the pistons with unvarying force to the front end of their respective cylinders. After the pistons *D E* have completed their stroke toward the front end of the cylinders *A B* the valve *L* will turn so as to open the passage *m*, when steam from the chamber *K* will pass into the cylinder *A* at the front side of the piston, and will move the latter about one-third of its back-stroke, at which time the valve *L* will turn to the position illustrated in Fig. 2, cutting off the steam in the chamber *K*, and permitting a portion of the steam in the cylinder *A* to flow through the passage *O* to the front end of the cylinder *B*, where it will expand and move the pistons to the completion of their back-stroke, in the manner before described when referring to the forward stroke of the pistons. When the pistons are upon their forward stroke, the valves *R S* are in the position illustrated in Fig. 2, the valve *R* preventing the

expanding steam from entering the exhaust *V*, while the steam on the front side of the piston *E* is allowed to exhaust into the chamber *V*.

It will be observed that the steam is cut off from the high-pressure cylinder when the piston therein has made about one-third of the stroke, and that a portion of the steam in the high-pressure cylinder is then allowed to expand against a piston of increased area in the expansive cylinder, whereby the stroke of the piston is completed with unvarying regularity and force, the expansion of the steam against an increased area at the point of cut-off counteracting the decreased pressure in the initial cylinder.

The invention is applicable to single direct-acting engines as well as to compound and crank engines.

The invention not only obviates the necessity of using a fly-wheel, but also of employing large cylinders, thus saving expense in the construction of the engine, as well as reducing the consumption of fuel.

What I claim as my invention, and desire to secure by Letters Patent, is—

1. The combination, with a high and low pressure cylinder, of connected pistons working therein, and valves for simultaneously cutting off the live steam after the pistons have completed a portion of their stroke and admitting steam from the high into the low pressure cylinder to complete the stroke, substantially as set forth.

2. In a steam-engine, the high-pressure cylinder and expansive cylinder having connected pistons, the one in the latter cylinder having a larger area than that in the former, and valves for cutting off the steam after the pistons have made a portion of their stroke and allowing a part of the steam then in the high-pressure cylinder to expand against the increased area of the piston in the expansive cylinder to complete the stroke, substantially in the manner and for the purposes described.

3. In a steam-engine, the high-pressure cylinder containing a piston and supplied with chambers *I K*, valves *J L*, ports *m M*, and passage *N*, combined with the expansive cylinder containing a piston on the same rod with the piston in the high-pressure cylinder, and being provided with a passage, *O*, valves *R S*, and ports *W X*, substantially as and for the purposes described.

Signed at New York, in the county of New York, and State of New York, this 7th day of November, A. D. 1884.

JOHN A. GROSHON.
